APPARATUS FOR DRYING FINELY DIVIDED MATERIALS WHILE SUSPENDED IN A GAS

Robert A. Caughey, Wilton, N. H.

Application December 12, 1945, Serial No. 634,417

11 Claims. (Cl. 34—57)

1

The present invention relates to a method of and apparatus for the rapid and efficient drying of finely divided low density materials, such as wood shavings, sawdust, ground leather, etc. Most materials of this general character are produced in such a manner that the particle size is widely variable and, consequently, require different drying periods to produce a uniformly dried product.

In the conventional dryer, the material to be dried is fed into one end of a rotary cylinder and gradually works its way toward the other end where it is discharged in the dry condition. The drying medium usually is heated air which is fed into the drying cylinder at the discharge end and passes through the dryer countercurrent to the flow of the material to be dried. In drying very light materials, it has been found that the heated air stream tends to carry the finer particles back towards the feed end. Consequently, the fine particles remain in the dryer longer than the larger particles and longer than is necessary if sufficient time is allowed for complete drying of the coarser particles. In either case, the product is not uniformly dried. If it is attempted to increase the drying rate by increasing the volume and velocity of the heated air, the tendency for the finer particles to be blown out of the dryer is increased. These conditions result in a relatively low heat efficiency and necessitate the use of special equipment for removal of the fine particles.

In accordance with the present invention, the particles of the material to be dried are classified during the process of drying in such a manner that the particles are retained in the drying chamber for a period of time substantially proportional to their mass and to the time required for the desired degree of drying. Thus the fine and light particles, which can be dried more rapidly, will pass through the drying chamber in a shorter period of time than the coarse and heavy particles. A uniformly dry product is obtained with a minimum expenditure of heat.

The invention will be more clearly understood from the following description in conjunction with the accompanying drawings, in which:

Fig. 1 is an elevational longitudinal view, partly in section, of an apparatus embodying the invention;

Fig. 2 is a sectional view taken upon the line 2—2 of Fig. 1;

Fig. 3 is a sectional view taken on the lines 3—3 of Figs. 1 and 2; and

2

Fig. 4 is a fragmentary plan view of a portion of the apparatus.

As illustrated in the accompanying drawing, an apparatus embodying the invention may comprise a drying chamber 10 having a substantially cylindrical wall 11, preferably, positioned with its axis substantially horizontal. The ends 8 and 9 of the wall 11 overlap slightly and are spaced slightly from one another as shown in Fig. 2 to provide a passage 12 into the interior of the drying chamber 10 for a purpose described hereinafter. A plenum chamber 13 extends longitudinally along the cylindrical wall 11 and comprises a bottom wall 14 and a side wall 15. The free end of the side wall 15 is secured to the outer surface of the cylindrical wall 11 in any suitable manner, such as by welding, and the free end of the bottom wall 14 overlaps and is secured to the end portion 9 of the cylindrical wall 11, as by welding. The ends of the cylindrical wall 11 and the ends of the plenum chamber 13 are closed by plates 16 and 17. One end of a tube 21 communicates with the lower end of a hopper 20 and the other end of the tube communicates with the interior of the drying chamber 10 through the plate 16. A feed screw 22 is positioned in the tube 21 and is adapted to feed finely divided material from the hopper 20 into the drying chamber 10. The shaft of the feed screw 22 projects through the wall 30 of the hopper 20 and carries a pulley 23. The armature shaft of a motor 24 is provided with a pulley 25 which is operatively connected to the pulley 23 by a belt 26.

The intake passage of a blower 30 communicates with a source (not shown) of heated air or other heated gaseous drying medium which is inert toward the material to be dried. The outlet of the blower 30 communicates with the interior of the plenum chamber 13 whereby heated air is forced into the plenum chamber 13 under pressure and is introduced tangentially into the drying chamber 10 through the longitudinally extending passage or orifice 12 at a velocity greater than is necessary to maintain the finely divided material to be dried in suspension. One end of a tubular passage 35 provides communication through the end plate 17 with the interior of the drying chamber 10 and the other end of the tube 35 communicates with the intake of an exhaust fan or blower 36. The exhaust fan 36 communicates through a tubular passage 37 with a cyclone separator 38. The orifice 12, preferably, is located along the lowest portion of the drying chamber 10.

A plurality of stationary baffles 40 are positioned

within the drying chamber adjacent the orifice 12 and are inclined from the orifice back toward the feed end of the drying chamber for a purpose explained hereinafter. One end of each of the baffles 40 is pivotally carried by a bolt 41 secured to a rod 42 extending longitudinally within the drying chamber 10 and secured to the end walls 16 and 17 by a nut 43 threaded upon each end thereof and engaging the end walls 16 and 17. Each bolt 41 passes through top and bottom flanges 3 and 4 respectively of the baffles 40. A washer 2 surrounding each bolt 41 serves as a spacing block between the overlapping ends 8 and 9. Nuts 39 and 44 threaded on each bolt 41 engage the top baffle flange 3 and the wall 14 secured to the overlapping end 9. The other end of each baffle 40 is pivotally carried by rivets 46 extending between the top baffle flange 3 and a rod 45 which extends longitudinally through the dry chamber parallel to the rod 42. The rod 45 is mounted in the end walls 16 and 17 in any suitable manner for longitudinal movement relative thereto whereby the inclination of the baffles 40 may be adjusted in synchronism.

In the operation of the apparatus, a heated gaseous drying medium is forced by the blower 30 into the plenum chamber 13 under sufficient pressure so that it will pass through the orifice 12 at a velocity approximately twice that necessary for the suspension of the coarser particles to be dried. The capacity of the exhaust fan 36, preferably, is slightly greater than that of the blower 30 so that the pressure within the drying chamber is slightly lower than that outside. The fan 36 withdraws air and the dried particles suspended therein and forces it through the passage 31 to the cyclone separator 38. The motor 24 causes the feed screw 22 to rotate and thus feed finely divided material to be dried from the hopper 20 into the drying chamber 10. As the stream of air passes through the orifice 12 it tends to move in a circular path at relatively high velocity adjacent the cylindrical wall of the drying chamber and carries the finely divided material in suspension. However, since the exhaust fan 36 operates to withdraw air from the drying chamber as fast as it enters, the air containing suspended particles to be dried tends to move in a spiral path from the feed end of the drying chamber to the discharge end thereof. During this travel of the suspended particles they are periodically and successively brought in engagement with the baffles 40 which act as deflectors deflect them back toward the feed end of the drying chamber. Since the angle of deflection of the particles will be the same and the carrying capacity of the heated air is proportional to the mass of the particles, the larger or heavier particles will be deflected a greater distance back towards the feed end of the drying chamber than the finer particles. The finer particles will be more quickly diverted by the air stream back into the normal stream of travel and will pass through the drying apparatus at a more rapid rate. It will be apparent that the time which the various particles are retained in the drying chamber will be substantially proportional to their mass and to the actual time required to dry them to the same moisture content and can be controlled by adjusting the angle of the baffles 40. By the practice of the invention, a final dried product is obtained in which all the particles have been dried to substantially the same moisture content.

I claim:

1. An apparatus for drying finely divided ma-

terial having particles requiring different drying periods which comprises a substantially cylindrical wall and end walls forming a drying chamber, means for introducing a stream of heated air tangentially to the cross section of the said cylindrical wall into the drying chamber at a velocity greater than that required to maintain said material in suspension and for withdrawing air from near one end of the drying chamber and tending to move said heated air in a helical path through said chamber, means for feeding said material into said helically moving stream near the other end of said chamber, and stationary means for successively deflecting said suspended material back away from the withdrawal end of said chamber and against the general direction of movement of the air in said chamber.

2. An apparatus for drying finely divided material having particles requiring different drying periods which comprises a substantially cylindrical wall and end walls forming a drying chamber, means for introducing a stream of heated air into the drying chamber tangentially to the cross section of said cylindrical wall forming an entrance orifice extending substantially its entire length at a velocity greater than that required to maintain said material in suspension and for withdrawing air near one end of the drying chamber and tending to move said heated air in a helical path through said chamber, means for feeding said material into said helically moving stream near the other end of said chamber, and stationary means positioned adjacent the wall of the drying chamber for successively deflecting said suspended material back away from the withdrawal end of said chamber and against the general direction of movement of the air in said chamber.

3. An apparatus for drying finely divided material having particles requiring different drying periods which comprises a substantially cylindrical wall and end walls forming a drying chamber, means for introducing a stream of heated air tangentially to the cylinder formed by said cylindrical wall into the drying chamber at a velocity greater than that required to maintain said material in suspension and for withdrawing air from near one end of the drying chamber thereby tending to move said heated air in a helical path through said chamber, means for feeding said material into said helically moving stream near the other end of said chamber, stationary means for successively deflecting said suspended material back away from the withdrawal end of said chamber against the general direction of movement of air in said chamber, and means controlling the distance which said suspended material is deflected back.

4. An apparatus for drying finely divided material having particles requiring different drying periods which comprises a substantially cylindrical wall and end walls forming a drying chamber, means for introducing a stream of heated air tangentially to the cylinder formed by said cylindrical wall into the drying chamber throughout substantially its entire length at a velocity greater than that required to maintain said material in suspension and for withdrawing air from near the opposite end of the drying chamber thereby tending to move said heated air in a helical path through said chamber, means for feeding said material into said helically moving stream near the other end of said chamber, stationary means positioned adjacent the wall of the drying chamber for successively deflecting

said suspended material back away from the withdrawal end of said chamber against the general direction of movement of the air in said chamber, said stationary means being adjustably arranged for controlling the distance which said suspended material is deflected back.

5. An apparatus for drying finely divided material having particles requiring different drying periods which comprises a substantially cylindrical wall and end walls forming a drying chamber, means for introducing a stream of heated air tangentially to the cross section of said cylindrical wall forming an entrance orifice extending substantially its entire length into the drying chamber at a velocity greater than that required to maintain said material in suspension and for withdrawing air from near one end of the drying chamber and tending to move said heated air in a helical path through said chamber, means for feeding said material into said helically moving stream near the other end of said chamber and longitudinally spaced stationary baffles positioned adjacent the wall of the drying chamber for successively deflecting said suspended material back away from the withdrawal end of said chamber and against the general direction of movement of the air in said chamber.

6. An apparatus for drying finely divided material having particles requiring different drying periods which comprises a substantially cylindrical wall and end walls forming a drying chamber, means for introducing a stream of heated air tangentially to the cylinder formed by said cylindrical wall forming an entrance into the drying chamber throughout substantially its entire length at a velocity greater than that required to maintain said material in suspension and for withdrawing air from near one end of the drying chamber thereby tending to move said heated air in a helical path through said chamber, means for feeding said material into said helically moving stream near the other end of said chamber and longitudinally spaced stationary baffles positioned adjacent the wall of the drying chamber and adjacent the region said air stream enters the drying chamber for successively deflecting said suspended material back away from the withdrawal end of said chamber, the drying chamber being positioned substantially horizontal and the entrance for said air stream into the drying chamber being substantially along the lowest region of the drying chamber.

7. An apparatus for drying finely divided material having particles requiring different drying periods which comprises a substantially cylindrical wall and end walls forming a drying chamber, means for introducing a stream of heated air tangentially to the cylinder formed by said cylindrical wall forming an entrance into the drying chamber throughout substantially its entire length at a velocity greater than that required to maintain said material in suspension and for withdrawing air from near the opposite end of the drying chamber thereby tending to move said heated air in a helical path through said chamber, means for feeding said material into said helically moving stream near the opposite end of said chamber, longitudinally spaced baffles positioned adjacent the wall of the drying chamber for successively deflecting said suspended material back away from the withdrawal end of the drying chamber against the general direction of movement of the air in said chamber, and means for adjusting the inclination of said baffles.

8. An apparatus for drying finely divided material having particles requiring different drying periods which comprises a substantially cylindrical wall and end walls forming a drying chamber, means for introducing a stream of heated air tangentially to the cylinder formed by said cylindrical wall forming an entrance into the drying chamber throughout substantially its entire length at a velocity greater than that required to maintain said material in suspension and for withdrawing air from near one end of the drying chamber thereby tending to move said heated air in a helical path through said chamber, means for feeding said material into said helically moving stream, longitudinally spaced baffles positioned adjacent the wall of the drying chamber and adjacent the region said air stream enters the drying chamber for successively deflecting said suspended material back away from the withdrawal end of said chamber against the general direction of movement of the air in said chamber, and means for adjusting the inclination of said baffles, the drying chamber being positioned substantially horizontal and the entrance for said air stream into the drying chamber being substantially along the lowest region of the drying chamber.

9. An apparatus for drying finely divided material having particles requiring different drying periods which comprises a cylindrical drying chamber, a plenum chamber extending substantially the entire length of the drying chamber and having a substantially coextensive orifice for introducing a stream of air tangentially into the cylindrical drying chamber, means for introducing heated air under pressure into the plenum chamber, means for withdrawing air from the opposite end of the drying chamber whereby said stream of heated air tends to move in a spiral path through the drying chamber, means for feeding the finely divided material into said spirally moving stream, and longitudinally spaced baffles positioned adjacent the wall of the drying chamber and said orifice and inclined to deflect said suspended material back away from the withdrawal end of the drying chamber.

10. An apparatus for drying finely divided material having particles requiring different drying periods including a longitudinal substantially cylindrical wall and end walls forming a drying chamber longitudinally through which the material travels during drying, a plenum chamber extending the length of the drying chamber and connected therewith by means forming a continuous tangential entrance orifice for the passage of gas into said chamber, said drying chamber having means forming a feed entrance for the material at one end and means forming an exit orifice for said material and gas at the end opposite the entrance and stationary deflectors within the drying chamber and distributed lengthwise of it arranged to return the heavier particles toward the entrance end.

11. An apparatus for drying finely divided material having particles requiring different drying periods including a longitudinal substantially cylindrical wall and end walls forming a drying chamber longitudinally through which the material travels during drying, a plenum chamber extending the length of the drying chamber and connected therewith by means forming a continuous tangential orifice for the passage of gas into said chamber, said drying chamber having means forming a feed entrance for the material at one end and means forming an exit orifice

for the material and gas at the end opposite the entrance and stationary deflectors within the drying chamber and distributed lengthwise of it adjustably arranged to return some of the particles toward the entrance end.
